FLOWER HOLDER

Paul F. K. Erbguth, Great Neck, N. Y.

Application January 30, 1953, Serial No. 23,369

Term of patent 14 years

(Cl. D35—3)

To all whom it may concern:

Be it known that I, Paul F. K. Erbguth, a citizen of the United States of America, residing at 120 Station Road, Great Neck, in the State of New York, have invented a new, original, and ornamental Design for a Flower Holder, of which the following is a specification, reference being had to the accompanying drawing, forming a part hereof, and wherein:

I claim:

The ornamental design for a flower holder, substantially as shown.

PAUL F. K. ERBGUTH.
